(57) CLAIM

The ornamental design for a convertible tote purse, as shown and described.

DESCRIPTION

FIG. 1 is a front view of a convertible tote purse according to my new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines in the figures indicate stitching and form a part of the claimed design.
